UNITED STATES PATENT OFFICE.

WILLIAM R. BRASHEAR, OF DAYTON, OHIO.

ANCHOR-ROD.

1,276,021.

Specification of Letters Patent. Patented Aug. 20, 1918.

Application filed June 4, 1917. Serial No. 172,739.

To all whom it may concern:

Be it known that I, WILLIAM R. BRASHEAR, citizen of the United States, residing at Dayton, in the county of Montgomery and 5 State of Ohio, have invented certain new and useful Improvements in Anchor-Rods, of which the following is a specification.

My invention relates to land anchors and more particularly to guy or strut anchors 10 for telephone and telegraph poles, fence posts, bridge anchors and other analogous devices employing a buried support. The invention relates more especially to a detachable anchor rod particularly applicable to 15 temporary structures, as for instance, temporary telephone and telegraph lines, fences and derricks or elevator supports.

The object of the invention is to simplify 20 the structure as well as the means and mode of operation of land anchors whereby they will not only be cheapened in construction, but will be more efficient in use, positive in 25 operation, easily and quickly attached and detached, and unlikely to get out of repair.

25 A further object of the invention is to provide an improved form of anchor rod engaging member from which the rod may be readily and quickly disengaged without the necessity of digging up the buried anchor.

With the above primary and other incidental objects in view as will more fully appear in the specification, the invention consists of the features of construction, the 35 parts and combinations thereof and the mode of operation or their equivalents, as hereinafter described and set forth in the claims.

Referring to the drawings, Figure 1 is 40 a sectional side elevation of the assembled land anchor forming the subject matter hereof, in operative position. Fig. 2 is a detail side elevation, partly in section, of the anchor rod and the engagement plate, showing in dotted lines the relative movement of the rod to effect the release of same from the plate. Fig. 3 is a detail perspective view of the engagement plate. Fig. 4 is a further modification.

50 Like parts are indicated by similar characters of reference throughout the several views.

It is the present practice in telephone and 55 telegraph construction, as well as in the erection of derricks and like constructions to employ as a land anchor to which the ends

of the guys or strut cables are connected, anchor rods having at their upper ends eyes or loops through which the guys or struts are engaged and screw threaded at their 60 lower ends. These anchor rods are extended through suitable holes in a log or large block of wood and are provided upon the protruding screw threaded end with a washer or collar and lock nuts. The expense of setting or burying such a land anchor is usually greater than the expense of the anchor rods themselves. The anchor rods themselves, however, are sufficiently valuable to warrant the recovery or salvaging 65 of such rods if it can be effected without the necessity of digging the anchor up or unearthing it.

To enable the recovery of the anchor rod with minimum labor and expense, with a 70 loss only of the engagement plate and the wood block known as the "dead man," is one of the primary objects of the present invention.

Referring to the drawing, 1 is the anchor 80 rod having at its upper end the eye or loop 2 through which is engaged the guy or strut cable 3. The rod 1 extends through a transverse hole 4 in a log or block of wood 5 technically known as the "dead man." The 85 rod 1 is preferably provided with a medial enlargement 6 substantially equal in diameter to the hole 4 in the dead man. At its lower end this enlarged medial portion 6 is provided with a tapered or conical extension 7 terminating in a shouldered conical head 8. The diameter of the head 8 is slightly less than that of the enlarged medial portion 6. Although the enlarged portion 90 6 is shown in the drawing somewhat extended and is the preferable form, this enlargement may be of comparatively short extent consisting substantially of only the tapered portion 7 as indicated at 7^a Fig. 4.

To prevent the withdrawal of the anchor 100 rod 1 from the hole 4 in the dead man 5, there is provided an engagement plate 9 having two oppositely disposed tongues or engagement jaws 10. These jaws 10 are preferably formed by slitting the plate 9 105 lengthwise to form parallel spaced slots and then connecting these slots transversely at a medial point. The tongues thus formed are bent slightly outward to enable the head 8 to be passed between them. To afford a 110 more extended engagement of the jaws 10 with the head 8, the jaws may be slightly

recessed as at 11 on their adjacent ends. These notches or indentations in the ends of the jaws, however, are not essential. The engagement plate 9 is of comparatively 5 heavy material suitably proportioned to the strain to which the anchor rod is to be subjected. The engagement plate is preferably of wrought iron, malleable iron or steel, although it may be of other material. It is 10 not desirable that it should possess a great degree of elasticity or spring, although the normal degree of elasticity of such metals is not objectionable. The head 8 of the anchor rod having been passed through the 15 engagement plate, intermediate the jaws 10, the latter are bent into close engagement with the neck 12 of the anchor rod, beneath the shouldered head 8. This is best done by striking the jaws or tongues 10 with a 20 hammer or a sledge. It will be understood that the anchor rod is extended through the dead man and engaged with the engagement plate before the parts are buried. The parts are then deeply and permanently buried. 25 When it is desired to disengage and remove the anchor rod 1, the guy or strut cable 3 is disengaged and the anchor rod 1 is driven longitudinally downward by sledge hammer blows upon the upper exposed end. The longitudinal movement of 30 the anchor rod 1 under the influence of such hammer blows forces the tapered or conical portion 7 of the rod between the jaws 10 of the engagement plate, thereby forcing said 35 jaws open as indicated by dotted lines in Fig. 2. The tapered head 8 enables the rod to penetrate more easily to greater depth during the initial downward movement of the anchor rod. The upper or largest diameter of the taper 7 being greater than the 40 diameter of the head 8 forces the jaws 10 apart such distance that upon the reversal of the direction of the anchor rod 1, the head 8 may readily pass between said jaws 45 and be drawn through the hole 4 in the dead man 5 and from the earth. The withdrawal of the anchor rod may be effected in any suitable manner or by any means. However, a convenient and effective means is provided 50 by a block and tackle connected at one end to the eye 2 and at its opposite end to any suitable support or abutment.

While as before stated, the enlargement of the anchor rod 1 may not necessarily extend beyond the tapered portion 7, the extended enlargement 6 is for the purpose of 55 excluding dirt or gravel from the hole 4 in the dead man, which might by becoming packed or locked therein interfere with the withdrawal of the anchor rod.

By the construction heretofore described, it will be understood that the anchor rod 1 may be readily removed by first forcing it 60 downward to separate the engagement jaws 10 sufficiently to permit the shouldered head

8 to pass between the jaws, and then withdrawing the rod longitudinally, leaving the dead man 5 and the anchor plate 9 buried in the ground.

From the above description it will be 70 apparent that there is thus provided a device of the character described, possessing the particular features of advantage before enumerated as desirable but which obviously is susceptible of modification in its form, 75 proportion, detail construction or arrangement of parts, without departing from the principle involved or sacrificing any of its advantages.

While in order to comply with the statute, 80 the invention has been described in language more or less specific as to certain structural features, it is to be understood that the invention is not limited to any specific details, but that the means and construction herein 85 described comprise but one mode of putting the invention into effect, and the invention is therefore claimed broadly in any of its possible forms or modifications within the scope of the appended claims.

Having thus described my invention, I 90 claim:

1. In a land anchor, an anchor rod having an integral terminal head, a longitudinally disposed cam surface adjacent to the head, 95 an engagement plate having jaws adapted to engage said rod adjacent to the head, the cam surface upon said rod being brought into engagement with the jaws to force said jaws apart a distance greater than the width 100 of the head by a longitudinal movement of the rod whereby the rod head may be disengaged from said jaws.

2. In a land anchor, an anchor rod, a detent member normally limiting the reciprocatory movement of the rod in one direction, and means for disengaging the rod from said member by an initial longitudinal movement of the rod in the opposite direction thereby permitting said rod to be subsequently withdrawn independent of the detent member.

3. In a land anchor, an anchor rod having a shouldered head, and a tapered portion the maximum diameter of which is greater than that of the head, and a detent engaging said shouldered head and movable out of engaging position by the engagement of said tapered portion upon a longitudinal movement of the rod.

4. In a land anchor, an anchor rod having a shoulder formed thereon, an inclined face upon said rod extending laterally beyond the limit of said shoulder, and a detent member adapted to be engaged with the shoulder but movable therefrom by said inclined face upon a longitudinal movement of the rod.

5. In a land anchor, an anchor rod, a detent plate having a flexible engagement tongue normally engaging with said rod,

and means for flexing said tongue out of engaging position by a longitudinal movement of the rod.

6. In a land anchor, an anchor rod, a detent plate having oppositely disposed engagement tongues adapted to engage with said rod to limit its longitudinal movement in one direction, and means for simultaneously flexing said tongues out of engaging 10 positions by a longitudinal movement of the rod in the opposite direction.

7. In a land anchor, an anchor rod, a detent plate having therein two substantially parallel spaced incisions connected medially 15 by a transverse incision to form two oppo-

sitely disposed tongues between which the rod is extended, said tongues being adapted to normally prevent the withdrawal of the rod, and means for disengaging said tongues from the rod by initially forcing the rod an 20 additional distance through said detent plate, thereby permitting the withdrawal of the rod.

In testimony whereof I have hereunto set my hand this 24th day of May, A. D. 1917. 25

WILLIAM R. BRASHEAR.
